UNITED STATES PATENT OFFICE.

FRANK C. GRADY, OF INDIANAPOLIS, INDIANA.

METER CONNECTION-BOX.

1,024,931.

Specification of Letters Patent. Patented Apr. 30, 1912.

Application filed September 15, 1910. Serial No. 582,158.

To all whom it may concern:

Be it known that I, FRANK C. GRADY, a citizen of the United States, and a resident of Indianapolis, in the county of Marion and State of Indiana, have invented a new and Improved Meter Connection-Box, of which the following is a full, clear, and exact description.

My invention relates to connection boxes, my more particular purpose being to produce a good form of connection box suitable for connecting wires or analogous electrical conductors with electric meters, my invention being especially adapted to facilitate the making and breaking of connections for a number of distinct purposes associated with the meters.

My invention further relates to the provision of a neck for joining my improved connection box with meters of various types.

Reference is to be had to the accompanying drawings forming a part of this specification, in which similar characters of reference indicate corresponding parts in all the figures.

Figure 1 is a front view partly broken away and partly in elevation, showing my improved connection box connected with an electric meter of ordinary construction by aid of a neck made for this purpose; Fig. 2 is a view partly broken away and partly in side elevation, showing the mechanism appearing in Fig. 1.

Generally speaking, my invention comprehends an inclosing box (see upper portions of Figs. 1 and 2) containing various binding posts, conducting bars and the like, most of which are permanently secured in position, the box being permanently mounted upon a wall. This box is spaced a little distance above the meter (see lower portions of Figs. 1 and 2) which may be of any approved type.

A neck (see middle of Figs. 1 and 2) made of metal and having substantially a frusto-pyramidal form, is so shaped as to fit contiguous portions of the connection box and the upper end of the meter, so as to encompass the space therebetween. By connecting wires or other conductors with certain of the binding posts in the box, and by temporarily making other connections within and below the connection box, the latter can be used for a large number of purposes, such as testing, changing from one meter to an-

other, or adjusting the meter for services of different character.

An electric meter is shown at 8 and is provided with lugs 9 whereby it may be mounted upon a wall, and is also provided with reading dials 10 for indicating the volts, watts or amperes, as the case may be, passing through the meter. The meter is further provided with a display panel 11 for indicating the general character of the meter.

At 12 is a seal for the meter. A neck 13 fits upon the upper portion of the meter and is provided upon its front face with lugs 14. This neck would be partially open in front except for a lid 15 which normally keeps it closed. The neck 13 is provided with a back 15^a having generally the form of a flat plate and provided with a slot 16, as will be understood from Fig. 2. A screw 16^a extends through the slot 16 and may be turned so as to clamp or release the back 15^a. At 17 is an inclosing box which contains various parts hereinafter described, all of said parts, together with the box 17, comprising my connection box.

The box 17 is provided with lugs 18, 19 whereby it may be temporarily or permanently mounted upon a wall. The lugs just mentioned are provided with holes 19^a, 19^b in order to receive screws and thus facilitate their connection with the wall. The box 17 is further provided with a back 17^a having generally the form of a back plate and disposed parallel with the plate 15^a. By loosening the screw 16^a, the back 15^a, and consequently the neck 13 which is integral with it, may be adjusted upwardly or downwardly and thus fitted neatly upon the top of the meter or disconnected therefrom, as the case may be. After the adjustment is made, the operator, by tightening the screw 16^a, firmly clamps the backs 15^a, 17^a together and thus rigidly secures the neck 13 in proper position.

The box 17 is provided with a lid 20 and this lid is mounted upon the box by aid of hinges 21. At 22 is a fastening which, by aid of a seal 23, is so secured as to prevent access to the interior of the box. Mounted within the box 17 is a plate 24 of insulating material, such as porcelain. The plate 24 is provided with annular lugs 25 which engage the back 17^a and space the plate 24 therefrom.

A metallic bar 26 is mounted upon the

plate 24 and is provided with a binding post 27. A spring clip 28 is also mounted upon the bar 26. Another metallic bar 29 is mounted within the box 17. This last-mentioned bar is provided at its lower end with a binding post 30. The bar 29 is further provided with a portion 31 extending horizontally, as will be seen from Fig. 1.

Mounted upon the bar 29 is a spring clip 32 which is in registry with the spring clip 28. A binding post 33 is mounted upon the portion 31. The clips 28, 32 are adapted to hold a fuse 34 which, however, is not used upon all occasions and is removable. At 35 15 is a spacing partition made of insulating material and extending some little distance outwardly from the plate 24. A screw 36 holds the partition 35 in position. Other spacing partitions 37, 38 are made of insulating material and are mounted in vertical alinement with the spacing partition 35, as will be understood from Fig. 1. A screw 39 extends through the spacing partition 37; this screw and the screw 36 extend through the annular lugs 25 (see Fig. 2) and assist in holding the plate 24 upon the back 17.

Disposed adjacent to the spacing partition 35 is a metallic bar 40 provided with a binding post 41. Adjoining the bar 40 and integral with it is another bar 42 provided with a binding post 43. Mounted near the upper edge of the plate 24 is a binding post 44 which is connected with a metallic bar 45, this bar being in contact with the bar 40. A bar 46 leads from the bar 45 to a binding post 47, and the bars 45, 46 are sunken into the back face of the plate 24. Spring clips 48, 49, are connected together and are in communication with the bar 45, and consequently with the bar 46. A spring clip 50 is mounted upon a metallic bar 51 and is in alinement with the spring clip 48. A binding post 52 is mounted upon the lower end 45 of the metallic bar 51. The metallic bars 26, 40, 29 and 51 are provided with contact plates 28^a, 28^b, 28^c, 28^d which may be used in testing—the terminals of the testing instrument being merely touched upon these contact plates.

Adjacent to the binding post 44 is a spacing partition 53 and next to the latter is a binding post 54. This binding post is connected by a metallic bar 55 with another binding post 56 disposed near the bottom edge of the plate 24. A metallic bar 57 is provided with a binding post 58, and mounted upon this bar is a spring clip 59. A metallic bar 60, integral with the metallic bar 57, extends out horizontally therefrom and is provided with a binding post 61.

A binding post 62 is mounted upon the

lower end of the metallic bar 57. Two other binding posts 63, 64 are connected together by a metallic bar 65. Spacing partitions 66, 65 68 are secured in position by aid of screws 67, 69, as above explained with reference to the securing of the spacing partitions 35, 37 by aid of the screws 36, 39.

A metallic bar 70 is disposed vertically 70 near one edge of the plate 24. Another metallic bar 71 is disposed horizontally and is integral with the bar 70. Mounted upon the upper end of the bar 70 is a binding post 72 and upon the lower end of this bar is another binding post 73. A metallic bar 74 connects together two binding posts 75, 76. At 77 is a fuse which is mounted in the clips 48, 50 but which is not in all instances essential. The fuse clips 49, 59 are arranged in alinement with each other and are adapted to temporarily hold a fuse 49^a.

To the left of the fuse 77 is a binding post 78 mounted upon the bar 71.

The operation of my device is as follows: 85 The meter 8 being connected with the box, as indicated in Figs. 1 and 2, and the various electrical connections being made, the meter is tested in accordance with well known rules or otherwise, as desired. The 90 arrangement of the various electrical connections is very convenient for making tests of different kinds and with meters varying in character.

Having thus described my invention, I 95 claim as new and desire to secure by Letters Patent:

1. The combination of a box-like member provided with a back plate, a neck movable relatively to said box-like member and provided with a portion for engaging a meter and with a flat portion having a slot, a bolt extending through said slot and engaging said plate for the purpose of clamping said neck relatively to said box-like member. 100

2. The combination of a box-like member provided with a back plate, a neck movable relatively to said box-like member and provided with a portion engaging said back plate, means for clamping said portion in different positions relative to said back plate, an electric meter engaging said neck, binding posts upon said meter, binding posts mounted within said box-like member, and conductors extending from said binding posts upon said meter to said binding posts within said box-like member. 110

In testimony whereof I have signed my name to this specification in the presence of two subscribing witnesses,

FRANK C. GRADY.
